Assistant Examiner — Michelle Marquart Christeon

(57) **CLAIM**

The ornamental design for a baby playpen, as shown and described.

DESCRIPTION

FIG. 1 is a front perspective view of a baby playpen, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view thereof, with the flap in an open configuration;

FIG. 9 is another perspective view thereof, wherein a top corner flap and a side corner flap are in an open view configuration; and,

FIG. 10 is a partial enlargement of FIG. 9.

The broken lines in FIGS. 9 and 10 represents the bounds of the enlargement taken from FIG. 9 and forms no part of the claimed design.

1 Claim, 10 Drawing Sheets
